VOLTAGE TRANSFORMATION APPARATUS

Raymond H. Sullivan, William H. Hutchins, and Cyril T. Wallis, Rochester, N. Y., assignors, by mesne assignments, to General Motors Corporation, Detroit, Mich., a corporation of Delaware

Application November 24, 1933, Serial No. 699,522

28 Claims. (Cl. 171—97)

This invention relates to voltage transformation apparatus, and more particularly to structure and a circuit for interrupting the current flow from a source, as well as for rectifying an alternating potential.

Altho quite a number of devices have been developed for accomplishing similar purposes, and particularly for the purpose of providing the high potentials necessary for the operation of an automobile radio receiver from the automobile storage battery, refinement and improvement are very desirable to increase the life, ruggedness, efficiency and operation of such devices so that they may better serve their purpose of eliminating more expensive and cumbersome apparatus.

It is therefore an object of this invention to provide rugged and efficient interrupting and rectifying apparatus, which apparatus has long life and good operating characteristics.

Another object of this invention is to provide mechanical interrupting and rectifying apparatus that is compact and may be easily and cheaply manufactured.

Another object of this invention is to provide apparatus employing a vibrating reed for actuating contacts for rectifying an alternating potential, which apparatus embodies means for minimizing sparking at the contacts actuated by the reed, and means for reducing and tending to eliminate high or radio frequency currents in the circuit of which said contacts are a part.

Another object of this invention is to provide apparatus embodying a vibrating reed for actuating both interrupting and rectifying contacts, which apparatus embodies means for minimizing sparking at the contacts and has condensers intimately associated therewith to by-pass and tend to eliminate high or radio frequency currents in the circuit of which the secondary contacts are a part.

Another object of this invention is to provide apparatus embodying a vibrating reed and having an improved magnet motor for actuating the vibrating reed.

Another object of this invention is to provide apparatus embodying a vibrating reed having contacts mounted thereon and cooperating resiliently mounted contacts on either side of the vibrating reed, which apparatus embodies a substantially U-shaped frame member with the reed and resilient contact supports insulatingly supported between the ends of the frame and an actuating magnet secured to the frame at a point opposite the end of the reed so that the electromagnet core extends substantially parallel to the axis of the reed and in close proximity to an armature mounted on the end of the reed.

Another object of this invention is to provide apparatus embodying a vibrating reed and a mag-

net motor for actuating the reed, in which the magnet has a core having an end projecting therefrom, and cooperating magnetic members providing a magnetic circuit from the end of the core opposite the projecting end to close proximity with the projecting end.

Another object of this invention is to provide apparatus embodying a vibrating reed having an armature on the end thereof and a magnet 10 motor for actuating the reed; the magnet having a projecting notched core portion cooperating with magnetic members that form a partial magnetic path between an end of the core and the projecting portion thereof, said magnetic members and notched portion having surfaces substantially parallel to and spaced from said armature.

Further objects and advantages of the present invention will be apparent from the following description, reference being had to the accompanying drawing wherein a preferred embodiment of the present invention is clearly shown.

In the drawing:

Fig. 1 is a circuit diagram of a preferred embodiment of the present invention.

Fig. 2 is a side elevation of a preferred structural embodiment of the present invention.

Fig. 3 is a fragmentary elevation taken substantially in the direction of the arrow 3 in Fig. 2.

Fig. 4 is a view of the actuating magnet structure taken substantially along the line, and in the direction of the arrows 4—4 of Fig. 2.

Fig. 5 is a fragmentary sectional view of the actuating magnet structure, and is taken substantially on a line, and in the direction of the arrows 5—5 in Fig. 4.

Fig. 6 is a magnified or exaggerated view showing a preferred arrangement of the contacts, and taken substantially on a line and in the direction of arrow 6—6 of Fig. 2.

With particular reference to Fig. 1, a transformer 10 has a core 12, a primary winding 14 that is preferably divided so as to have sections 16 and 18 and a center tap 20, and a secondary winding 22 having a center tap 24. The center tap 20 of the primary winding is preferably connected thru an inductance or choke 26 to one terminal of a battery 28. The ends of the primary winding 14 are connected to contacts 30 and 32 respectively, which contacts are engageable with contacts 34 and 36 respectively, that are mounted on a resilient reed or contact carrying member 38 and are electrically connected thereto. The resilient reed 38, in this form, is normally unbiased so that the contacts are normally in a disengaged position. The vibrating reed 38 is preferably connected to ground at 40, and is connected to the other terminal of the battery 28 through a switch 42, and preferably thru an inductance or choke 44. An electromag-

net 46 has a core 48 in magnetic relation with the reed 38 and a winding 50, one end of which winding is connected to a primary contact such as 32 while the other end is connected to ground at 52.

The ends of the secondary winding 22 are connected to contacts 54 and 56 respectively, which contacts are alternately engageable with contacts 58 and 60 respectively. The contacts 58 and 60 are mounted on the resilient reed 38, and electrically connected thereto. The secondary center tap 24 is connected to a suitable output lead 62 preferably thru an inductance or radio frequency choke 64 and an inductance or audio frequency choke 66, which choke coils are not particularly a part of the present invention, but rather, provide part of a filter to adapt the device to be utilized for supplying potential to a device such as a radio receiver. A condenser 68 is connected to the center tap 24 and to ground at 70. The vibrating reed 38 is connected to another suitable output lead 72 thru the inductance or choke 44. Condensers 74 and 76 are respectively connected to the ends of the audio frequency choke 66, and to the output lead 72, which condensers also form a part of the filter. Condensers 78 and 80 each have one side connected to the resilient reed 38, and the other side of the condenser 78 is connected to the contact 54 while the other side of the condenser 80 is connected to the contact 56.

With particular reference to Figs. 2, 3, 4 and 5, the structure of a preferred form of vibrator unit, to be used in a circuit such as that shown in Fig. 1, is illustrated. In these figures, reference numerals similar to those previously used refer to similar parts. In this structure, a preferably substantially U-shaped frame 100 having arms 102 and 104 and a closed end 106 is utilized as a support. This frame is preferably made of a metal or conducting material having comparatively low temperature coefficient of expansion. The contact and vibrator assembly comprises spacers 108, 110, 112, 114 and 116 that are preferably metallic; insulating spacers 118, 120, 122, 124, 126, 128 and 130; and metallic shims 132 and 134; as well as resilient contact springs 136, 138, 140 and 142; contact carrying spring reinforcing and stop members 144, 146, 148 and 150; and the resilient reed 38. The assembly formed by these parts is clamped and secured between the ends of the arms 102 and 104 by screws 152 and 154 having cooperating nuts 156 and 158 and cooperating washers 160, 162, 164 and 166; or other suitable fasteners. The screws 152 and 154 are insulatingly separated from the contact carrying springs and the resilient reed by insulating spacers, not shown, or other suitable insulating means. The insulating spacers 118, 120, 122, 124, 126 and 128 insulatingly separate the current carrying parts of the assembly, such as the contact carrying springs and resilient reed, from each other, and also, in cooperation with the metallic spacers 108, 110, 112, 114 and 116, and the insulating spacer 130, as well as the stop members 144, 146, 148 and 150, properly space the contact carrying members from the resilient reed so that by minor adjustment of the contact carrying members and stop members, the stationary contacts are properly positioned for engagement with the reed contacts during vibration of the reed. The contact carrying springs, stop members and resilient reed preferably extend substantially parallel to each other and substantially parallel to the arms 102 and 104 toward the end

106 of the frame. The extending ends of the stop members 144, 146, 148 and 150 are preferably bent outwardly toward their respective contact carrying springs 136, 138, 140 and 142, and those 5 contact carrying springs are preferably biased against the ends of those stop members so that the position of the contacts that are carried by the contact carrying members may be adjusted by bending the stop members, and vibratory 10 movement of the contacts and their carrying members is limited.

The resilient reed 38 is preferably provided with a connecting lug such as 170, which lug is preferably grounded to the frame 100 thru a lead 172 that is preferably soldered to the frame as at 174 and 176. The contact carrying springs also preferably have connecting lugs such as a lug 178 on the spring 136 that is connected to a lead such as 180; a lug 182 on the spring 138 that is connected to leads such as 184 and 186; a lug 188 on the spring 140 that is connected to a lead such as 190; and a lug 192 on the spring 142 that is connected to a lead such as 194. A lead such as 196 is connected to the lug 170 for the purpose of making external connections to the resilient reed 38. The insulating spacer 130 preferably has an opening 198 therethru, thru which the leads 180, 184, 190, 194 and 196 extend. This provides an anchor and guide for the leads.

30 The resilient reed 38 preferably has secured to the surface thereof, such as at 200, a covering or layer of fibrous material such as cloth or paper to deaden the sound thereof and quiet the operation of the device. An armature 202 of magnetic material is secured to the end of the reed by rivets such as 204 or other suitable fastening means. This armature preferably has a portion 206 that extends beyond the end of the reed.

The core 48 of the electromagnet 46 preferably 40 has a portion 208 that projects beyond the end of the winding 50 and extends thru an aperture 210 in a magnetic member 212 and an aperture 214 in the end 106 of the frame. The electromagnet is then secured to the end of the frame 45 by riveting the end of the portion 208 as at 216. The other end of the electromagnet core preferably has a portion 218 that projects beyond the end of the winding and provides a shoulder as at 220 which provides a support for an insulating 50 winding support member 222. The portion 218 preferably has an offset portion 224 such that the end of the core presents two substantially parallel end surfaces that are not in the same plane, and a surface 226 that is preferably substantially perpendicular to the parallel end surfaces. The magnetic member 212 has side portions 228 and 230 that are preferably substantially parallel to the longitudinal axis of the core and which act as pole pieces that preferably have 55 pole tips 232 and 234, which pole tips project toward the portion 218 of the core. Edges 236 and 238 of the pole tips 232 and 234 respectively are preferably substantially parallel, and preferably substantially in alignment with the surface 226 of the portion 218. End surfaces 240 and 242 of the pole tips 232 and 234 respectively, which surfaces form the pole ends or faces, are preferably curved so that their distance apart and their distance from the edges 244 and 246 of the portion 218 increases with the distance from the edges 236 and 238 respectively. This construction and arrangement results in an increase in the reluctance of the flux path between the magnetic pole surfaces with the distance from the edges 236 and 238 or across the pole faces in one

direction. The tendency of this construction and arrangement is therefore to increase the flux density toward one side of the pole tips. A disc-like member of insulating material 248 located intermediate the end of the winding 50 and the magnetic member 212 provides an insulating support for the end of the winding. The winding is preferably insulatingly separated from the core by a layer of insulating material 250, and is preferably covered by a layer of insulating material 252.

The relative location of the armature 206 and the magnetic circuit provided by the pole tips 232 and 234 and the core portion 218 is preferably such that the armature is eccentric to the pole tips and to the magnetic flux threading the pole tip, altho in close proximity thereto.

In this preferred embodiment of the present invention, the condensers 78 and 80 are preferably secured to offset portions 256 and 258 of the arms 102 and 104 intermediate those arms and the resilient reed 38. These condensers preferably have metallic containers which serve as one terminal thereof so that the condensers are thus grounded to the frame and connected to the resilient reed through the lead 172. The condensers are preferably mounted so that the other connecting leads 260 and 262 thereto are connected to the contact carrying springs 136 and 138 in a manner such that the leads are short.

As indicated in the magnified or exaggerated view shown in Fig. 6, the primary contacts 30 and 32 are preferably adjusted so that the normal gaps intermediate the contacts 30 and 34 and the contacts 36 and 32 are less than the gaps between the contacts 54 and 58 and the contacts 60 and 56 respectively. This may be accomplished by either adjusting the contacts 30 and 32 so that they are closer together or by spacing the contacts 34 and 36 from the reed 38, or in some similar manner. This feature permits the primary circuit to be closed before and opened after the secondary circuit.

In the operation of this device in the circuit shown, the resilient reed 38 is normally unbiased, so that the contacts 30 and 34, 36 and 32, 54 and 58, and 60 and 56 respectively, are normally disengaged. When the switch 42 is closed, the circuit is closed from one side of the battery 28 to the reed 38 and to ground at 40. This completes a circuit to the electromagnet winding 50 thru the primary winding section 18 since one end of the winding is grounded at 52 and the other end of the winding 50 is connected to the battery thru the primary winding section 18. The circuit thus formed thru the electromagnet winding effects a current flow therethru and causes the electromagnet to actuate the reed and move it to a position such that engagement of the contacts 36 and 32 and 60 and 56 respectively is effected. The engagement of the contacts 36 and 32 short circuits the electromagnet winding 50 by connecting the end thereof to ground at 40 thru those contacts. The resulting deenergization of the electromagnet releases the reed so that its resilience, deformation and mass carry it to a position to effect engagement of the contacts 54 and 58 and 30 and 34 respectively. Similar cycles of operation result in vibration of the reed at a rate dependent upon the natural vibrating period and thus alternate making and breaking of the contacts.

When the contacts 36 and 32 are closed, the current flow thru the section 18 of the primary winding creates a flux that produces a potential

5 in the secondary winding 22. This secondary potential is applied to the output lead 62 from the center tap 24, and to the output lead 72 thru the contacts 60 and 56. Engagement of the contacts 30 and 34 closes a circuit thru the section 16 of the primary winding after the disengagement of the contacts 36 and 32 opens the circuit thru the section 18. The resulting flow of current thru the section 16 of the primary winding creates a flux in a direction opposite to that which was created by the section 18. This, in turn, induces a potential in the secondary winding 22 opposite in polarity to that produced by the current in the section 18. However, the potential applied to the output leads 62 and 72 is of the same polarity in each instance, since the other end of the secondary winding is connected to the output lead 72 thru the contacts 54 and 58. The resistance of the electromagnet winding 50 is preferably high so that the current flow thru the section 18 of the primary winding and the electromagnet, while the contacts are open, as well as its shunt effect across the section 16 are not appreciably high with respect to the current flow thru the sections 18 and 16 when the contacts 36 and 32 or 30 and 34 respectively, are closed.

30 It has been found that unless some means are provided for the prevention of sparking at the contacts, and the improvement of the efficiency 35 of the device, that the sparking is detrimental to the life and operation of the unit and the efficiency is considerably reduced. Hence, the condensers 78 and 80 have been provided, each of which condensers is connected from the reed 38 to a secondary contact or end of the secondary winding. Furthermore, these condensers, connected in this manner, provide a by-pass or conductor path for reducing and tending to eliminate high and radio frequency currents from the secondary circuit, as well as from the primary circuit when the primary circuits are closed. These high and radio frequency currents are bypassed to ground at 40. Hence, the leads 260 and 262 are preferably made as short as possible 40 to increase the effectiveness of this by-passing action and to prevent radiation therefrom. By utilizing the metallic or conductive container for the condensers 78 and 80, and utilizing that container as a terminal for one side of the condenser, the condensers are easily and conveniently grounded directly to the frame 100 by soldering or similar means.

45 It has also been found that by mounting the contacts 30, 32, 54 and 56 on resilient contact carrying members, and adjusting the position of the contacts 30 and 32 so that contact is made between the contacts 36 and 32 somewhat before contact is made between the contacts 60 and 56, the characteristics and efficiency of the circuit are further improved.

50 To make the operation of the condensers 78 and 80 more clear to those skilled in the art, and to explain more fully how the reduced contact 55 sparking and increased efficiency are obtained through the use of these condensers, the following discussion, together with approximate mathematical representations are herein presented. Broadly, when the reed swings from one side to the other, the circuit to the primary winding is opened on one side and closed to the other side. This causes the magnetic flux to reverse in direction. Therefore, the flux builds up to a maximum value in one direction, then drops to zero and builds up to a maximum value in the other direction. This alternating magnetic field gen-

erates an alternating voltage in both the primary and the secondary windings. The second set of contacts on the reed vibrates in synchronism with the primary circuit interrupting contacts to rectify the alternating voltage and currents of the secondary windings.

At the time when the primary current and the magnetic field are building up, the counter E. M. F. or voltage generated in the primary winding at any instance after closing the primary circuit, may be represented by:

$$e_p = -\frac{N_p}{10^8} \frac{d\phi}{dt} \text{ volts} \quad (1)$$

Where:

e_p = the voltage induced in the primary winding.
 N_p = the number of turns in the primary winding.

$\frac{d\phi}{dt}$ = the rate of change of the magnetic field.

The (−) sign in front of the right member of the Equation 1 shows that the induced voltage opposes the impressed battery voltage. Neglecting the resistance of the primary winding, at any instant:

$$E_b = e_p \quad (2)$$

or

$$E_b - e_p = 0 \quad (3)$$

where E_b = the impressed battery voltage.

The voltage generated in the secondary coil by the changing magnetic field is:

$$e_s = -\frac{N_s}{10^8} \frac{d\phi}{dt} \text{ volts} \quad (4)$$

From (1) and (4) it may be seen that the ratio of secondary to primary voltage is:

$$\frac{e_s}{e_p} = \frac{-\frac{N_s}{10^8} \frac{d\phi}{dt}}{-\frac{N_p}{10^8} \frac{d\phi}{dt}} = \frac{N_s}{N_p} \quad (5)$$

where:

e_s = the induced voltage in the secondary winding, and

N_s = the number of turns in the secondary winding.

When the primary contacts are opened and the primary impressed voltage is thus removed, voltages are generated in both windings due to the decrease of the magnetic field strength. However, the polarity of the induced voltage in this instance is reversed to that of the first instance.

When the primary contacts are closed:

$$e_{pc} = E_b e^{-\frac{Rt}{L_p}} \quad (6)$$

or

$$e_{pc} = E_b \frac{1}{e^{\frac{Rt}{L_p}}} \quad (7)$$

where:

e_{pc} = the voltage generated in the primary winding at any time (t) after the primary contacts are closed.

L_p = the inductance of the primary circuit in henries.

R = the primary resistance in ohms.

e = a constant (2.718)

t = the time in seconds that the primary contacts are closed.

In systems such as the present, where the primary and secondary windings are interlinked with the completely closed magnetic circuit, the resistance of the primary winding is compara-

tively low, and the time t is comparatively small, the value of the exponent

$$\left(\frac{Rt}{L_p}\right)$$

in (7) is practically zero, and may be considered as zero for practical calculations. Therefore, Equation 7 becomes:

$$e_{pc} = E_b \frac{1}{e^0} = E_b \quad (8)$$

From (8) it may be seen that the induced voltage in the primary winding, at any time between the closing of the primary contacts and the time of opening those contacts, is equal to the impressed voltage.

When the secondary winding is interlinked with the primary winding by the same magnetic circuit, the secondary voltage is:

$$e_{sc} = e_{pc} \frac{N_s}{N_p} \quad (9)$$

where:

e_{sc} = the voltage generated in the secondary winding when the primary contacts are closed.

In order to generate constant voltage in the windings, the rate of change of flux

$$\frac{d\phi}{dt}$$

must be constant. That is:

$$\frac{d\phi}{dt} = C = \frac{\phi}{t} \quad (10)$$

substituting (10) in (1):

$$e_{pc} = \frac{N_p \phi}{10^8 t} \quad (11)$$

and, solving (11) for ϕ :

$$\phi = \frac{10^8 e_{pc} t}{N_p} \quad (12)$$

When the primary contacts are opened, and if no resistance or capacity is shunted across the primary contacts or secondary contacts or the primary or secondary windings or both, the inductive voltage across the contacts will tend to increase to an indefinitely large value. However, in such an instance, an arc forms at the contacts and has the same effect as connecting a resistance across the contacts or primary or secondary windings. Such an arc, as well as being harmful to the contacts, dissipates energy and is in effect a power loss. This condition may be shown mathematically as follows:

$$e_{po} = E_b \left(1 - e^{-\frac{Rt}{L_p}}\right) \quad (13)$$

where:

e_{po} = the primary voltage at any time (t) after the primary contacts are opened.

From (13) it may be seen that if the resistance across the contacts is indefinitely large at the time of opening the contacts, the exponent

$$\left(\frac{Rt}{L_p}\right)$$

in (13) is ∞ indefinitely large.

Then:

$$e_{po} = E_b (1 - e^{\infty}) \quad (14)$$

$$e_{po} = \infty \text{ volts}$$

If a very low value of resistance were connected across the contacts or windings, the exponent

$$\left(\frac{Rt}{L_p}\right)$$

in (13) is practically zero. Hence, if t is small and is comparatively large, then:

$$\begin{aligned} e_{po} &= E_b(1-e^t) & (15) \\ e_{po} &= E_b(1-1) \\ e_{po} &= 0 \end{aligned}$$

Equations 14 and 15 show that it is necessary to have some resistance or some equivalent suppressor across the contacts or one or both of the windings if the voltage across the contacts is to be kept below any value that will create an arc at the contacts. These equations also indicate that for best results, the effective value of this suppressor or resistance should be kept within predetermined limits. The desired result, in this respect, is therefore to control the voltage across the contacts with respect to the separation of the contacts so that sparking is reduced or eliminated. By connecting the condenser or condensers of the proper capacity across the contacts or primary or secondary windings, this result may be quite efficiently attained.

When the primary contacts are closed, the current flow through the primary winding builds up a magnetic field in the magnetic circuit or core. Energy from the battery is required to establish or build up this magnetic field. Therefore, the magnetic field interlinking the primary winding at the time of opening the primary contacts represents stored magnetic energy. When, therefore, condensers are utilized for the reduction or elimination of sparking at the contacts, the voltage generated in the transformer windings by the decay of the magnetic flux in the core, charges the condenser. The stored magnetic energy is thus transformed into electrostatic energy.

The magnetic energy stored in the magnetic circuit at the time when the primary contacts are open may be represented by the following equation:

$$W_m = \frac{1}{2} L_p i_b^2 \quad (16)$$

Where:

W_m =the magnetic energy in joules, and

i_b =the primary magnetizing current.

The electrostatic energy stored in a condenser is

$$W_e = \frac{1}{2} C e_c^2 \quad (17)$$

where:

W_e =the electrostatic energy in joules;

C =the capacity of the condenser in farads; and

e_c =the peak voltage across the condenser.

Since the same energy is merely transformed in form from magnetic to electrostatic energy, and neglecting the resistance energy loss, which is negligible in a circuit having low resistance such as that in the present system, the electrostatic energy stored is equal to the magnetic energy, thus

$$W_m = W_e \quad (18)$$

or

$$\frac{1}{2} L_p i_b^2 = \frac{1}{2} C e_c^2$$

and

$$e_c = \sqrt{\frac{L_p}{C}} i_b = \sqrt{\frac{L_p}{C}} i_s \quad (19)$$

The frequency of energy transformation from one form to the other is dependent upon the natural electrical period of the circuit. That is,

$$f = \frac{1}{2\pi\sqrt{LC}} \text{C. P. S.} \quad (20)$$

The peak value of the voltage across the condenser and winding occurs twice in a cycle; that is, there is a positive and a negative peak. The first peak value of voltage occurs at the time of the first quarter cycle after the contacts are opened.

$$T = \frac{1}{f} \quad (21)$$

where

f =the frequency in cycles per second; and

T =the time for one discharge cycle.

$$T = \frac{1}{\frac{1}{2\pi\sqrt{LC}}} = 2\pi\sqrt{LC} \text{ seconds} \quad (22)$$

The time in seconds required for the first quarter cycle is

$$t_0 = \frac{1}{4} T = \frac{\pi}{2} \sqrt{LC} \quad (23)$$

Equations 19 and 23 show that for a given transformer winding and corresponding inductance L , the peak voltage across the contacts and also the rate of voltage rise may be controlled through the selection of the capacity of the condenser that is connected across the contacts, or across a winding. Since the contacts are in engagement before they are opened or separated, the voltage across the contacts is zero at the instant of separation and increases to a maximum value in the time required for one quarter cycle. That is, after the time of contact separation, there is a steady increase in the voltage across the contacts. Also, after the instant of separation, there is a steady increase in separation between the contacts. If, then, arcing of the contacts is to be eliminated, the ratio of the rate of voltage rise across the contacts to the rate of contact separation must remain below that at which arcing will occur. It is easily understood that substantially the same result, in this respect, can be obtained by connecting a condenser across the primary or secondary winding, or across the respective contacts.

Since the effect of a condenser connected across an inductance or winding, as in the present instance, is to shift the phase of the current in the winding with respect to the voltage, and consequently to shift the phase of the induced voltages, it may be seen that such a condenser or condensers, when of the proper value, may be easily and conveniently utilized to bring the points of zero current value of the secondary current into synchronism with the points of interruption of the primary current; or to adjust the time constant of the secondary circuit to synchronism to that of the primary synchronism. This is desirable in the present instance, since both the primary and secondary contacts are actuated by a single reed. Furthermore, since the beneficial result of the condenser for storing magnetic energy does not increase with the size of that condenser after a predetermined capacity is reached, a value of condenser capacity is chosen which most nearly effects the desired ultimate result of eliminating sparking at the contacts and improving the efficiency of the system.

By connecting two condensers in series across the secondary winding, and grounding the common connection of those condensers, as shown in the present form of this invention, the condensers serve to accomplish still another purpose; namely, that of providing a by-pass to ground for high and radio frequency currents.

Since the vibrating reed may be conveniently grounded in the circuit shown, it is particularly convenient to thus ground the vibrating reed and to connect each of the two condensers to the reed, and to connect one terminal of each to one of the secondary contacts. This manner of connecting the condensers is beneficial both electrically and to the structure and compactness of the vibrator unit.

While the embodiment of the present invention as herein disclosed, constitutes a preferred form, it is to be understood that other forms might be adopted, all coming within the scope of the claims which follow.

What is claimed is as follows:

1. In combination with a transformer having primary and secondary windings, a vibrating means having a single magnetic vibrator motor, and provided with series of contacts for interrupting a primary current and for rectifying an alternating secondary voltage, some of said contacts also controlling the magnetic vibrator motor, and means for reducing sparking at the contacts, the last mentioned means also providing a by-pass tending to eliminate high and radio frequency currents from the rectifying contacts.

2. In combination with a transformer having primary and secondary windings, a vibrating means having a single magnetic vibrator motor, and provided with series of contacts for interrupting a primary current and for rectifying an alternating secondary voltage, some of said contacts also controlling the magnetic vibrator motor, and means for reducing sparking at the contacts, the last mentioned means also providing a by-pass tending to eliminate high and radio frequency currents from the rectifying contacts, said last mentioned means comprising condensers having a capacity suited to the reduction of sparking and each being connected to the vibrating means and to the rectifying contacts.

3. In combination with a voltage change device, a vibrating means having a single magnetic vibrator motor, and provided with series of contacts for interrupting a primary current and for rectifying an alternating secondary voltage, the contacts for interrupting the primary current also controlling the magnetic vibrator motor, means for bringing the points of zero current value of the secondary current substantially into phase with the interruptions of said primary current, said last mentioned means also providing a by-pass for high and radio frequency currents from the rectifying contacts.

4. In combination, a transformer having primary and secondary windings and vibrating means for interrupting a primary current and for rectifying a secondary voltage, said vibrating means being unitary and having a ground connection, means for changing the phase of the secondary current, the last mentioned means providing a by-pass for high and radio frequency currents.

5. In combination, a transformer having primary and secondary windings and circuits therefor, and vibrating means for interrupting a primary current and for rectifying a secondary voltage, said vibrating means being unitary and having a direct ground connection, and means for bypassing high and radio frequency currents from one of said circuits to ground.

6. In combination, a transformer having primary and secondary windings and circuits therefor, and vibrating means for interrupting a primary current and for rectifying a secondary volt-

age, said vibrating means being unitary and having a direct ground connection, and means for bypassing high and radio frequency currents from one of said circuits to ground, the last mentioned means comprising a plurality of condensers connected to the vibrating means and to one of said circuits.

7. In combination, a transformer having primary and secondary windings and circuits therefor, and vibrating means for interrupting a primary current and for rectifying a secondary voltage, said vibrating means being unitary and having a direct ground connection, and condensers connected to the vibrating means and to the circuit of the secondary winding for bypassing high frequency currents from said circuit to ground.

8. In combination with a voltage change device having primary and secondary windings and circuits therefor, a vibrating means having a ground connection and a magnetic vibrator motor, and provided with series of contacts for interrupting a primary current and for rectifying an alternating secondary voltage, the contacts for interrupting the primary current also controlling the magnetic vibrator motor, and means for storing some of the magnetic energy of the voltage change device, that is present when the primary current interrupting contacts are opened, in the form of electrostatic energy, the energy storing means also providing a by-pass to ground for high frequency currents.

9. In combination with a transformer having a tapped primary winding and a secondary winding and circuits therefor, a vibrator device having motive means connected to a source of primary current, and a set of contacts for controlling the motive means and for alternately connecting different parts of the primary winding to the source of primary current to cause the flux in said transformer to vary from a positive to a negative value periodically, a second set of contacts connected with the secondary winding of the transformer to rectify the secondary voltage, and means for storing some of the magnetic energy that is present in the transformer at the time of breaking the contacts that control the primary winding, said means comprising condensers connected to the vibrator and to the contacts that are connected to the secondary winding, said condensers having a capacity such that the voltage across the secondary contacts after those contacts are opened is reduced to limit arcing at the contacts.

10. In combination with a transformer having a tapped primary winding and a secondary winding and circuits therefor, a vibrator device having motive means connected to a source of primary current, said vibrator device being grounded, and a set of contacts for controlling the motive means and for alternately connecting different parts of the primary winding to the source of primary current to cause the flux in said transformer to vary from a positive to a negative value periodically, a second set of contacts connected with the secondary winding of the transformer to rectify the secondary voltage, and means for storing some of the magnetic energy that is present in the transformer at the time of breaking the contacts that control the primary winding, said means comprising condensers connected to the vibrator and to the contacts that are connected to the secondary winding, said condensers having a capacity such that the voltage across the secondary contacts after those

contacts are opened is reduced to limit arcing at the contacts, and said condensers providing a by-pass to ground for high frequency currents from one of the circuits.

11. In combination, a transformer having primary and secondary windings and a vibrating means for interrupting a primary current and contacts for rectifying a secondary voltage, and means for controlling the rate of secondary voltage rise in proper relation to the separation of said contacts to prevent arcing at the contacts, the last mentioned means comprising condensers each connected to said vibrating means and each connected to a secondary contact, said condensers also providing a by-pass for high frequency currents.

12. In combination with a transformer having a tapped primary winding and a secondary winding and circuits therefor, a vibrator device having motive means connected to a source of primary current, and a set of contacts for alternately connecting different parts of the primary winding to the source of primary current to cause the flux in said transformer to vary from a positive to a negative value periodically, a second set of contacts connected with the secondary winding of the transformer to rectify the secondary voltage, and means for improving the efficiency of the combination, said means comprising condensers connected to said vibrator device and to one each of one of said sets of contacts and pre-adjusted contact carrying members so constructed and arranged that the primary contacts break after the contacts that rectify the secondary voltage.

13. In combination with a transformer having a tapped primary winding and a secondary winding and circuits therefor, a vibrator device having motive means connected to a source of primary current, said vibrator device being grounded, and a set of contacts for alternately connecting different parts of the primary winding to the source of primary current to cause the flux in said transformer to vary from a positive to a negative value periodically, a second set of contacts connected with the secondary winding of the transformer to rectify the secondary voltage, and means for improving the efficiency and operation of the combination, said means comprising condensers, each of which condensers is connected to said vibrator device and to a contact of one of said sets of contacts, said condensers serving both to limit sparking at the contacts and to by-pass high frequency currents, and means so constructed and arranged that the contacts of said sets make and break at different times.

14. In combination with a transformer having a primary winding and a tapped secondary winding and circuits therefor, a vibrator device having motive means connected to a source of primary current, and a set of primary contacts for controlling the motive means and for effecting intermittent energization of the primary winding from the source of primary current, a second set of contacts connected with the secondary winding of the transformer to rectify the secondary voltage, and means for improving the efficiency of the combination, said means comprising condensers connected to the vibrator device and to one each of one of said sets of contacts and pre-adjusted contact carrying members so constructed and arranged that contacts of one of said sets break after the contacts of the other of said sets.

5 15. In combination with a transformer having primary and secondary windings, a motor operated vibrating means provided with series of contacts for interrupting a primary current and for rectifying an alternating secondary voltage and a capacity across the secondary winding of the transformer for reducing high and radio frequency currents at the rectifying contacts, said capacity comprising a plurality of condensers connected to ground.

10 16. In combination with a transformer having primary and secondary windings, a motor operated vibrating means provided with series of contacts for interrupting a primary current and for rectifying an alternating secondary voltage and a capacity across the secondary winding of the transformer for reducing high and radio frequency currents at the rectifying contacts, said capacity comprising a plurality of condensers and 15 a connection extending from a point between the contacts to ground.

20 17. In combination with a transformer having primary and secondary windings, a motor operated vibrating means provided with series of contacts for interrupting a primary current and for rectifying an alternating secondary voltage and a capacity across the secondary winding of the transformer for reducing high and radio frequency currents at the rectifying contacts, said capacity comprising a plurality of condensers and 25 a connection in series and a connection from said condensers to ground.

30 18. In combination with a transformer having primary and secondary windings, a motor operated vibrating means provided with series of contacts for interrupting a primary current and for rectifying an alternating secondary voltage and means forming a by-pass operative to reduce high and radio frequency currents at the rectifying contacts and also operative to reduce sparking at the contacts, said means comprising a plurality of condensers across the secondary winding of the transformer and connected to ground.

35 19. In combination with a transformer having primary and secondary windings, a motor operated vibrating means provided with series of contacts for interrupting a primary current and for rectifying an alternating secondary voltage and means forming a by-pass operative to reduce high and radio frequency currents at the rectifying contacts and also operative to reduce sparking at the contacts, said means comprising a plurality of condensers connected in series across the transformer and having a connection from a 40 point between the condensers to ground.

45 20. In combination with a transformer having primary and secondary windings, a motor operated vibrating means provided with series of contacts for interrupting a primary current and for rectifying an alternating secondary voltage and means forming a by-pass operative to reduce high and radio frequency currents at the rectifying contacts and also operative to reduce sparking at the contacts, said means comprising a plurality of condensers connected in series across the transformer and having a connection from a point between the condensers to ground at a point between said condensers.

50 21. In combination with a transformer having primary and secondary windings, a motor operated vibrating means provided with series of contacts for interrupting a primary current, rectifying a secondary current and for controlling the operation of the motor for operating the vibrating means, and means forming a by-pass operative

to reduce high and radio frequency currents at the rectifying contacts, said means comprising a plurality of condensers connected across the secondary winding of the transformer and to ground.

22. In combination with a transformer having primary and secondary windings, a motor operated vibrating means provided with series of contacts for interrupting a primary current, rectifying a secondary current and for controlling the operation of the motor for operating the vibrating means, and means forming a by-pass operative to reduce high and radio frequency currents as the rectifying contacts, said means comprising a plurality of condensers connected in series across the transformer and to ground at a point between said condensers.

23. In combination with a transformer having primary and secondary windings, a motor operated vibrating means provided with series of contacts for interrupting a primary current, rectifying a secondary current and for controlling the operation of the motor for operating the vibrating means, and means forming a by-pass operative to reduce high and radio frequency currents at the rectifying contacts, said means being also operative to reduce sparking at the contacts and comprising a plurality of condensers connected across the secondary winding of the transformer and to ground.

24. In combination with a transformer having primary and secondary windings, a motor operated vibrating means provided with series of contacts for interrupting a primary current, rectifying a secondary current and for controlling the operation of the motor for operating the vibrating means, and means forming a by-pass operative to reduce high and radio frequency currents at the rectifying contacts, said means being also operative to reduce sparking at the contacts and comprising a plurality of condensers connected in series across the secondary winding of the transformer and to ground at a point between said condensers.

25. In combination with a transformer having primary and secondary windings, a motor operated vibrating means provided with series of contacts for interrupting a primary current and for rectifying an alternating secondary voltage and means for bringing the points of zero potential value of the secondary voltage into synchronism with the interruptions of the primary current and

for reducing high and radio frequency currents at the rectifying contacts, said means comprising a plurality of condensers connected across the secondary of the transformer and to ground.

26. In combination with a transformer having primary and secondary windings, a motor operated vibrating means provided with series of contacts for interrupting a primary current and for rectifying an alternating secondary voltage and means for bringing the points of zero potential value of the secondary voltage into synchronism with the interruptions of the primary current and for reducing high and radio frequency currents at the rectifying contacts, said means comprising a plurality of condensers connected in series across the secondary of the transformer and connected to ground at a point between said condensers.

27. In combination with a transformer having primary and secondary windings, a motor operated vibrating means provided with series of contacts for interrupting a primary current, rectifying a secondary current and for controlling the operation of the motor for operating the vibrating means, and means for bringing the points of zero potential value of the secondary voltage into synchronism with the interruptions of the primary current and for reducing high and radio frequency currents at the rectifying contacts, said means comprising a plurality of condensers connected across the secondary of the transformer and to ground.

28. In combination with a transformer having primary and secondary windings, a motor operated vibrating means provided with series of contacts for interrupting a primary current, rectifying a secondary current and for controlling the operation of the motor for operating the vibrating means, and means for bringing the points of zero potential value of the secondary voltage into synchronism with the interruptions of the primary current and for reducing high and radio frequency currents at the rectifying contacts, said means comprising a plurality of condensers connected in series across the secondary of the transformer and connected to ground at a point between said condensers.
